UNITED STATES PATENT OFFICE.

JOHN A. HELVIN, OF NEW YORK, N. Y., AND HENRY VAN HOEVENBERGH,
OF ELIZABETH, NEW JERSEY.

WIRE-SPlicer.

SPECIFICATION forming part of Letters Patent No. 326,906, dated September 22, 1885.

Application filed February 11, 1885. (No model.)

To all whom it may concern:

Be it known that we, JOHN A. HELVIN and HENRY VAN HOEVENBERGH, citizens of the United States, residing, respectively, in New York, in the county and State of New York, and Elizabeth, in the county of Union and State of New Jersey, have invented certain new and useful Improvements in Wire-Splacers, of which the following is a specification.

10 The invention relates to the class of devices employed for coupling or splicing the ends of wires with each other.

The object of the invention is to provide convenient and efficient means for joining or 15 coupling wires which are more or less ductile, and which may not be securely fastened together by the ordinary methods without extreme care.

The invention is designed especially for 20 use in connection with copper conductors employed for electrical purposes, and to render it possible to form a reliable electrical connection and a strong and secure joint without necessitating the employment of pliers. In 25 constructing copper lines it is considered requisite that the wires should not be handled by pliers, for the indentations which would thus be made would greatly weaken the wire and render it more liable to stretch and break 30 at such points.

The invention consists in constructing a short sleeve or thimble of strong metal—such as brass—having two longitudinal perforations of suitable size for receiving the two conductors. Through these perforations it is designed that the ends of the conductors to be 35 united shall be inserted in opposite directions. The protruding end of each conductor is wrapped by hand about the portion of the 40 other conductor adjacent to the thimble or sleeve.

For the purpose of conveniently holding the sleeve so that the wires may not be twisted while the joint is being made, a wrench or 45 holding-clamp of peculiar construction is employed. The thimble or sleeve is formed with two recesses upon opposite sides for receiving the jaws of the clamp. The clamp is of metal, and its jaws are designed to fit closely within 50 the recesses. When the sleeve is applied to copper wires, and, in fact, to wires of almost

any material, and held by the clamp, the ends may be readily wrapped about the conductors by hand without the necessity of employing the pliers. The protruding ends are 55 of such length that they may be readily handled, and after a sufficient number of convolutions have been made the ends may be cut off by suitable wire-cutters.

It has been heretofore proposed to couple 60 or joint wires by means of a double metallic tube or sleeve, through which the wires are inserted and into which they are soldered. The ends of these conductors have in these instances, however, been either bent slightly, 65 so that they will readily draw back through the tubes while being soldered, or else they have been bent backward upon themselves and the ends each inserted into a shallow recess formed in the corresponding end of the 70 sleeve. In the present invention the wires are each wrapped about the other and securely held in position, whether soldered or not, and at the same time insuring more perfect electrical connections.

It is usually desirable in coupling electrical conductors that the joints should be soldered for the purpose of securing reliable and permanent electrical connections. In applying 75 solder, however, to copper conductors it has 80 been found difficult to prevent the copper from annealing. By applying the sleeve or coupling described in this application it is found that the amount of metal contained both in the coupling and the clamp and 85 brought into immediate contact with the wire is sufficient to prevent the points at which the solder is applied from becoming greatly heated, and thus the wire is prevented from being annealed.

In the accompanying drawings, Figure 1 shows the sleeve as applied to conductors, and Fig. 2 is a cross-section of the sleeve with the wires in place. Fig. 3 is a side view of the clamp which it is preferred to employ.

Referring to the figures, A represents a metallic thimble or sleeve through which are formed longitudinal perforations a' and a'' . Through these perforations it is designed that the conductors L' and L'' shall be inserted, the ends 100 l' and l'' projecting from the opposite ends, respectively. These projecting ends are re-

spectively designed to be wrapped about the wire entering at the same end; and for the purpose of holding the coupling securely while this operation is being effected the 5 clamp shown in Fig. 3 is employed. This clamp is constructed with a handle, C. Upon the handle C there is a screw, c, entering a corresponding point in the head D. Upon the head D there is formed a stationary jaw, 10 d, and a movable jaw, d', is pivoted to a supporting-lever d''. The end of the screw c presses against the jaw d', and by turning the handle in one direction this last-named jaw is forced forward toward the jaw d. The clamp 15 is preferably of metal, and the two jaws are designed to fit closely within two recesses, e' and e'', formed in the opposite sides of the coupling or sleeve A. When the clamp is applied to the coupling, the ends l' and l'' of 20 the wires may be very readily wrapped by hand about the portions of the conductors L' and L'' adjacent thereto.

Conductors coupled in this manner form a strong joint, and one which, even though the 25 metal be very ductile, cannot be pulled apart, for the bent portions, by striking against the head of the coupling A, will be prevented from uncoiling; and a very important advantage secured is that the using of pliers for manipulating the wire is dispensed with, and at 30 no point is there formed an indentation or a twist in the wire.

When the conductors have been thus wrapped the one about the other, the ends may 35 be cut off. If it is desired, solder may be applied at the points f' and f'', for the purpose of both securing a more perfect and permanent electrical connection, and also for affording a stronger joint. The heat which is occasioned 40 by applying the solder will be dispersed throughout the metal immediately about the points f' and f'', and as the clamp D is of metal there is sufficient metal in immediate connection with the conductors to prevent them from 45 becoming overheated and from annealing.

The two perforations through the thimble are preferably parallel with each other throughout

their length, and the recesses formed in the sides are cut parallel with a plane passing through both apertures. In this manner a 50 very compact coupling is formed.

We claim as our invention—

1. The combination, substantially as hereinbefore set forth, with two wires, of a coupling consisting of a metallic sleeve having two 55 longitudinal apertures formed therethrough, through which apertures said conductors are inserted in opposite directions, the end of each conductor being wrapped about the other conductor, substantially as described. 60

2. The combination, substantially as hereinbefore set forth, with two wires, of a coupling consisting of a metallic sleeve having two longitudinal apertures formed therethrough, through which said wires extend in opposite 65 directions, and having recesses formed upon its opposite sides, substantially as described.

3. A metallic coupling for wires, consisting of a sleeve having apertures formed therethrough longitudinally, and having recesses 70 formed in its opposite sides, substantially as described.

4. The coupling for wires, consisting of the thimble or sleeve A, having longitudinal apertures a' and a'', and the recesses e' and e'', the 75 bottoms of which recesses are parallel with a plane passing through both of said apertures.

5. The combination, substantially as hereinbefore set forth, with two wires, of a coupling consisting of a metallic sleeve having two apertures formed therethrough, through which said conductors are inserted in opposite directions, the end of each conductor being wrapped about the other conductor, substantially as described, and being united therewith at the 80 joint thus formed by being soldered. 85

In testimony whereof we have hereunto subscribed our names this 5th day of February, A. D. 1885.

JOHN A. HELVIN.

HENRY VAN HOEVENBERGH.
